UNITED STATES PATENT OFFICE

2,488,704

COLLAPSIBLE TRAY OR CARTON

Kenneth T. Butterly, Kalamazoo, Mich., assignor
to Sutherland Paper Company, Kalamazoo,
Mich., a corporation of Michigan

Application April 9, 1948, Serial No. 19,982

10 Claims. (Cl. 229—35)

1

This invention relates to improvements in collapsible trays or cartons.

The main objects of this invention are:

First, to provide a collapsible tray or carton formed of an integral blank which may be easily and quickly erected either by hand or by relatively simple machines designed for the purpose.

Second, to provide a tray or box formed of an integral blank which may be shipped or transported in the knockdown and quickly set up, as above stated, and one which when set up or erected is relatively strong and rigid, both the side end walls being supported in an upright position.

Further objects relating to details and economies of the invention will definitely appear from the description to follow. The invention is pointed out in the claims.

A preferred embodiment of the apparatus for carrying out the method of the invention is clearly illustrated in the accompanying drawing in which;

Fig. 1 is a top perspective view of a box or tray embodying my invention in fully erected position.

Fig. 2 is a fragmentary view in longitudinal section illustrating parts in partially set up or erected position and one of the stages in such erection.

Fig. 3 is a fragmentary perspective view illustrating another stage in the erection of the parts.

Fig. 4 is a plan view of the blank in the flat.

Fig. 5 is a fragmentary longitudinal section of a modified form or embodiment of my invention with the box in erected position.

Fig. 6 is a fragmentary plan view of the blank in the flat of the modified form of my invention shown in Fig. 5.

My improved collapsible box or tray is formed of an integral blank shown in the flat in Fig. 4 and comprising a bottom 1, side walls 2—2 and end walls 3—3. The side walls are hingedly connected to the bottom by score lines, conventionally illustrated at 4—4, while the end walls are hingedly connected to the bottom by the scores, conventionally illustrated at 5—5. The end walls 3—3 have corner flaps 6—6 extending from the ends thereof and hingedly connected thereto at 7—7. The end edges 8—8 of the side walls are aligned with the hinging score 5 for the end walls to the bottom. The hinging scores 7 connecting the corner flaps to the end walls are aligned with the hinging scores 4—4 connecting the side walls to the bottom. The bottom edges 9 of the corner flaps are inclined diagonally outward as viewed in the blank and substantially spaced from the end edges 8 of the side walls.

The side walls have slits 10 therein extending diagonally outward from their end edges, the inner ends of the slits being preferably closely adjacent to the bottom edges of the side walls. The slits 10 have portions 11 at their inner ends

2

disposed at an angle to the main portions of the slits or at a less angle relative to the top or bottom edges of the side walls than the outer portions of the slits as considered relative to their open ends. This results in a deflectable side portion 12 at each end of each side wall.

The corner flaps have inwardly inclined notches 13 in their side edges with slits 14 extending inwardly from the notches and aligned with the bottom edges of the notches. This results in triangular tongue-like portions 15 which engage within the inner sides of the side walls when the parts are in fully erected position with the notches and slits of the corner flaps engaged with the slits of the side walls.

The cutting away and spacing of the inclined bottom edges of the corner flaps from the end edges of the side walls, as viewed in the blank, greatly facilitates the erection of the tray or box, particularly when erected by machine. In erection the side walls are turned or swung upwardly as indicated in Fig. 2, preferably in a somewhat inwardly inclined relation; the end walls are then swung upwardly and the corner flaps turned inwardly as the end walls are swung to upright position.

The corner flaps engage the deflectable portions 12 of the side walls and move them inwardly so that the inclined bottom edges 9 of the corner flaps easily pass into the slits of the side walls and completely swing to erected position. When released the side walls spring outwardly against the corner flaps with the bottom edges of the notches and slits 14 engaging the upper edges of the slits 10 of the side walls, and with the tip portions 15 of the corner flaps locked on the inner side of the side walls as shown in Figs. 1 and 5.

While this greatly facilitates machine erection it is also advantageous in hand erection, that is, it is possible to very quickly erect the box or tray by hand if desired; however, the boxes or trays are used in large commercial quantities and machine erection is very economical.

The structure of the present application greatly facilitates such machine erection as the inclined lower edges of the end inclined bottom edges of the corner flaps pass easily and freely through the slits 10 of the side walls and the parts become interlocked without special manipulation, and at the same time a very secure retaining engagement is effected with the end edges of the side walls abutting the inner sides of the ends, thereby holding both side and end walls in vertical position.

In the modification shown in Figs. 5 and 6 the end walls have outer portions 16 which are aligned with the hinging score 5 and inwardly inclined inner portions 17 terminating at the slits 10. This further facilitates the erection of the box or tray as the bottom edges 17 are engaged by the bottom edges 9 of the corner flaps as the

parts are moved to erected position, thus providing a further camming action in the deflecting of the deflectable portions 12 of the side walls. Otherwise, the parts are as in the structure previously described.

Attention is directed in this connection to my pending application Serial No. 638,165, filed December 29, 1945. The present invention is a very substantial improvement on the structure there illustrated in that it greatly facilitates the erection, both by hand and machine.

I have illustrated and described my invention in highly practical forms, both from the standpoint of the completely erected article and practicability in both hand and machine erection. I have used the terms "side" and "end" walls as matters of convenience in description, but it will be understood that the boxes or trays are of various shapes and designed for packaging various articles, pies, for example. It is believed that the use of the terms "side" and "end" walls materially simplifies the terminology of the specification and claims. I have not attempted to illustrate or describe other embodiments or adaptations of the invention as it is believed this disclosure will enable those skilled in the art to embody or adapt the invention as may be desired.

Having thus described my invention, what I claim as new and desire to secure by Letters Patent is:

1. A collapsible tray or box formed of an integral blank comprising a bottom and side and end walls hingedly connected thereto, and corner flaps hingedly connected to the ends of the end walls and foldable on the outer sides of the side walls when they are in erected position, the hinge connections for the corner flaps to the end walls being aligned in the flat blank with the hinge connection for the side walls to the bottom, the ends of the side walls being in the flat blank aligned with the hinge connections for the end walls to the bottom, the bottom edges of the corner flaps in the flat blank being spaced from and outwardly inclined relative to the end edges of the side walls, the side walls having slits opening at their end edges and extending diagonally outward from adjacent their bottom edges, the outer end portions of the slits being disposed at a less angle than their inner portions, the corner flaps having notches downwardly inclined from their side edges opposite their hinge connections to the end walls and inwardly extending diagonally disposed slits aligned with the lower edges of the notches, the said inclined bottom edges of said corner flaps and the said notches in the said side edges thereof facilitating entrance of the bottom edges of the corner flaps through said slits in said side walls and the engagement of the lower edges of the notches and slits in the side edges of the corner flaps with the outer edges of the said side wall slits and the supporting of the end walls when erected in supported engagement with the end edges of the side walls.

2. A collapsible tray or box formed of an integral blank comprising a bottom and side and end walls hingedly connected thereto, and corner flaps hingedly connected to the ends of the end walls and foldable on the outer sides of the side walls when they are in erected position, the hinge connections for the corner flaps to the end walls being aligned in the flat blank with the hinge connection for the side walls to the bottom, the ends of the side walls being in the flat blank aligned with the hinge connections for the end walls to the bottom, the bottom edges of the

corner flaps in the flat blank being spaced from and outwardly inclined relative to the end edges of the side walls, the side walls having slits opening at their end edges and extending diagonally outward from adjacent their bottom edges, the corner flaps having notches in their side edges opposite their hinge connections to the end walls, the said inclined bottom edges of said corner flaps and the said notches in the said side edges thereof facilitating entrance of the bottom edges of the corner flaps through said slits in said side walls and the engagement of the lower edges of the notches in the side edges of the corner flaps with the outer edges of the said side wall slits and the supporting of the end walls when erected in supported engagement with the end edges of the side walls.

3. A collapsible tray or box formed of an integral blank comprising a bottom and side and end walls hingedly connected thereto, and corner flaps hingedly connected to the ends of the end walls and foldable on the outer sides of the side walls when they are in erected position, the bottom edges of the corner flaps in the flat blank being spaced from and outwardly inclined relative to the end edges of the side walls, the side walls having slits opening at their end edges and extending diagonally outward therefrom, the outer end portions of the slits being disposed at a less angle than their inner portions, the corner flaps having notches in their side edges opposite their hinge connections and having inwardly extending diagonally disposed slits extending the notches, the said inclined bottom edges of said corner flaps and the said notches in the said side edges thereof facilitating entrance of the bottom edges of the corner flaps through said slits in said side walls and the engagement of the lower edges of the notches and slits in the side edges of the corner flaps with the outer edges of the said side wall slits with portions of the corner flaps in interlocking engagement with the side walls.

4. A collapsible tray or box formed of an integral blank comprising a bottom and side and end walls hingedly connected thereto, and corner flaps hingedly connected to the ends of the end walls and foldable on the outer sides of the side walls when they are in erected position, the bottom edges of the corner flaps in the flat blank being spaced from and outwardly inclined relative to the end edges of the side walls, the side walls having slits opening at their end edges and extending diagonally outward therefrom, the outer end portions of the slits being disposed at a less angle than their inner portions, the corner flaps having inwardly extending diagonally disposed slits opening to their side edges opposite their hinge connections to the end walls, the said inclined bottom edges of said corner flaps facilitating entrance of the bottom edges of the corner flaps through said slits in said side walls.

5. A collapsible tray or box formed of an integral blank comprising a bottom and side and end walls hingedly connected thereto, and corner flaps hingedly connected to the ends of the end walls and foldable on the outer sides of the side walls when they are in erected position, the hinge connections for the corner flaps to the end walls being aligned in the flat blank with the hinge connection for the side walls to the bottom, the end edges of the side walls in the flat blank having outer portions aligned with the hinge connections for the end walls to the bottom and having inwardly inclined inner portions, the

bottom edges of the corner flaps in the flat blank being outwardly inclined and substantially spaced from the end edges of the side walls, the side walls having slits opening at their end edges and extending diagonally outward from adjacent their bottom edges, the outer end portions of the slits being disposed at a less angle than their inner portions, the corner flaps having notches downwardly inclined from their side edges opposite their hinge connections and having inwardly extending diagonally disposed slits aligned with the lower edges of the notches, the said inclined bottom edges of said corner flaps and the said notches in the said side edges thereof facilitating entrance of the bottom edges of the corner flaps through said slits in said side walls and the engagement of the lower edges of the notches and slits in the side edges of the corner flaps with the outer edges of the said side wall slits with portions of the corner flaps interlocking within portions of the side walls above their slits, and the supporting of the end walls when erected in supported engagement with the end edges of the side walls.

6. A collapsible tray or box formed of an integral blank comprising a bottom and side and end walls hingedly connected thereto, and corner flaps hingedly connected to the ends of the end walls and foldable on the outer sides of the side walls when they are in erected position, the hinge connections for the corner flaps to the end walls being aligned in the flat blank with the hinge connection for the side walls to the bottom, the end edges of the side walls in the flat blank having outer portions aligned with the hinge connections for the end walls to the bottom and having inwardly inclined inner portions, the bottom edges of the corner flaps in the flat blank being outwardly inclined and substantially spaced from the end edges of the side walls, the side walls having slits opening at their end edges and extending diagonally outward from adjacent their bottom edges, the outer end portions of the slits being disposed at a less angle than their inner portions, the corner flaps having slits opening to their side edges opposite their hinge connections to the end walls, the said inclined bottom edges of said corner flaps facilitating entrance of the bottom edges of the corner flaps through said slits in said side walls and the engagement of the lower edges of the slits in the side edges of the corner flaps with the outer edges of the said side wall slits with portions of the corner flaps interlocking within portions of the side walls above their slits.

7. A collapsible tray or box formed of an integral blank comprising a bottom and side and end walls hingedly connected thereto, and corner flaps hingedly connected to the ends of the end walls and foldable on the outer sides of the side walls when they are in erected position, the hinge connections for the corner flaps to the end walls being aligned in the flat blank with the hinge connection for the side walls to the bottom, the side walls having slits opening at their end edges and extending diagonally outward from adjacent their bottom edges of the slits being disposed at a less angle than their portions, the corner flaps having notches downwardly inclined from their side edges opposite their hinge connections and having inwardly extending diagonally disposed slits aligned with the lower edges of the notches, the lower edges of the slits of the corner flaps en-

gageable with the upper edges of side wall slits with portions of the corner flaps interlocking within portions of the side walls above their slits.

8. A collapsible tray or box formed of an integral blank comprising a bottom and side and end walls hingedly connected thereto, and corner flaps hingedly connected to the ends of the end walls and foldable on the outer sides of the side walls when they are in erected position, the side walls having diagonally disposed inwardly inclined slits opening at their end edges and having inwardly inclined edge portions extending to the said slits, the corner flaps having outwardly inclined bottom edges spaced from the end edges of the side walls in the blank, the corner flaps having slits downwardly inclined from their side edges opposite from their hinge connections and spaced from their bottom edges to provide upwardly directed tongue portions engageable with the inner sides of the side walls, the adjacent inclined edges of the corner flaps and the side wall end edges in the blank facilitating the interlocking engagement of the corner flaps with the side walls when the tray is erected.

9. A collapsible tray or box formed of an integral blank comprising a bottom and side and end walls hingedly connected thereto, and corner flaps hingedly connected to the ends of the end walls and foldable on the outer sides of the side walls when they are in erected position, the side walls having diagonally disposed inwardly inclined slits opening at their end edges, the corner flaps having outwardly inclined bottom edges spaced from the end edges of the side walls in the blank, the corner flaps having slits downwardly inclined from their side edges opposite from their hinge connections and spaced from their bottom edges to provide upwardly directed tongue portions engageable with the inner sides of the side walls, the adjacent inclined edges of the corner flaps and the side wall end edges in the blank facilitating the interlocking engagement of the corner flaps with the side walls when the tray is erected.

10. A collapsible tray or box formed of an integral blank comprising a bottom and side and end walls hingedly connected thereto, and corner flaps hingedly connected to the ends of the end walls and foldable on the outer sides of the side walls when they are in erected position, the side walls having diagonally disposed inwardly inclined slits opening at their end edges having inwardly inclined edge portions extending to the said slits, the bottom edges of the corner flaps being spaced outwardly in the flat blank from the hinge connections for the end walls to the bottom.
